UNITED STATES PATENT OFFICE.

JAMES J. KEYS, OF BROOKLYN, NEW YORK.

ARCH-SUPPORT.

1,317,021.

Specification of Letters Patent. Patented Sept. 23, 1919.

Application filed January 25, 1918. Serial No. 213,748.

To all whom it may concern:

Be it known that I, JAMES J. KEYS, a citizen of the United States, residing at Brooklyn, in the county of Kings and State of New York, have invented new and useful Improvements in Arch-Supports, of which the following is a specification.

This invention relates to boots and shoes, and more especially to shanks; and the object of the same is to produce an arch support which is to an extent an improvement over the device covered in my U. S. Patent, No. 1,219,331, dated March 13, 1917. In the said patent provision was made for supporting the shank of the shoe so as to prevent a falling of the same such as often takes place. My present improvement is designed more particularly to prevent a twisting of the shank with reference to the sole and the heel, which twisting sometimes takes place when the wearer's foot is not accurately centered over the shank or is pushed to one side or the other in the act of walking. We often observe shoes whose heels are "run over" or worn away at one side. This condition flows from the fact that the wearer is not accustomed to put his or her foot squarely down onto the ground, and the usual remedy is metallic heel plates which prevent the rapid wear of the heel. But I find that the custom of so handling the foot as to run over the heel also has its effect on the shank of the shoe, and if the habit is excessive the shank is sometimes twisted to such an extent that it is loosened from the heel and perhaps torn from the upper. The purpose of the present invention is to amplify the structure of my patented arch support so as to give it greater rigidity at both its front and rear ends, thereby rendering it useful for preventing a twisting of the shank as well as preventing a falling of the same under the influence of a falling arch or wear by a flat-footed person. This object is carried out by providing the device with flanges at its front and rear ends, as more specifically described below and shown in the drawings herein.

A further object of the invention resides in the provision of an arch support whereby the weight of the body will be equally applied to the heel and arch portions of the shoe and thereby operate to produce a natural and perfect balance to the body of the wearer while walking.

A still further object of the invention is

to provide an arch support adapted for rigid application against the under surface of the shank, and a spring secured to the most prominently arched side of the plate which will operate to lift the shank in an upward direction and establish a cushioning effect against the arch of the foot. I find that by adding a spring to the structure and interposing the same between the plate and the shank of the shoe, it has a prominent tendency toward holding the foot in proper place and preventing the foot from being crowded to the forepart of the shoe. As a further purpose for providing this arrangement, I have in mind eliminating those conditions between the foot and arch which commonly are the direct cause of corns and bunions, stagnation of the ligaments and the creation of undue pressure on the sides of the joints and toes while the user is in the act of walking.

Figure 1, is an inverted perspective view of the arch support showing the same applied.

Fig. 2, is a plan view of the arch support detached from the shoe.

Fig. 3, is a sectional view on the line 3—3, of Fig. 1.

Fig. 4, is a sectional view on the line 4—4, of Fig. 1.

As to the shoe, it is necessary only to refer to the heel H and shank S, and while I speak of "shoe" herein the piece of foot wear might obviously be a boot. My improved arch support consists of a metallic plate 1 having preferably the contour shown in Fig. 1 which is a bottom plan view of the left shoe. The companion plate will be correspondingly shaped to fit the right shoe, but need not be shown or described herein. This plate is to be secured by screws 2 or other similar fastening devices to the bottom of the shank S. By preference the plate is provided with a medial longitudinally disposed rib 3 as set forth in prior patent already referred to, the center of this rib being rather deep or pronounced, while its ends fade out or terminate short of the front and rear ends of the plate itself. This rib defines two leaves respectively numbered at 4 and 5 in the drawings, the leaf 4 at the outer side of the rib being curved upward or arched longitudinally to correspond with the longitudinal curvature of the shank S, while it is practically flat transversely. The leaf 5 at the other side of the rib is curved upward

or arched both longitudinally and transversely. However, this is the specific construction of the plate as set forth in my prior patent, and it affords the advantages 5 recited therein.

Coming now more particularly to the details of the present improvement, we may assume that the two leaves 4 and 5 lie substantially in planes which stand at a wide or 10 extremely obtuse angle to each other like the sides of a roof of which the rib 3 constitutes the ridge. The plate 1 is now hipped across its front end to form a triangular panel 6; and when the plate is produced by stamping, as will doubtless be 15 the case, the presence of the panel 6 gives great rigidity to the front end of the plate. At its rear end the latter is provided with a depending flange 7 which lies against the 20 front face of the heel H as seen in Fig. 1 and is curved to conform therewith as seen in Fig. 1. In Fig. 4 I have shown a part of the leaf 4 as broken away and the flange 7 I have provided with holes 8, although this 25 is a detail which may or may not be employed and which may be used or not if it is employed. While screws or other fastening devices 2 pass through the leaves into the shank S, I may use screws or other 30 fastening devices passing through the holes 8 into the heel H or not as desired, and I have indicated three of them at 9 in full lines in Fig. 1.

The manner of forming and applying 35 this plate will now be obvious. Its use as an arch support is substantially the same as that set forth in my prior patent and need not be repeated here. The advantage of the hipped panel 6 is that it gives greater 40 rigidity to the front end of the plate and therefore more firmly supports the forward portion of the shank S. The advantage of the flange 7 (which should be in strict contact with the heel H whether it is fastened 45 thereto or not) is that it both gives greater rigidity to the rear end of the plate 1 and prevents a lateral motion of the heel with respect to the shank, so that in effect and

to quite an extent it overcomes the rocking of the shank brought about by the peculiar 50 manner in which some persons handle their feet as above suggested. Even if the flange 7 be not fastened to the heel as indicated at 9, the ordinary curvature which the front face of the heel possesses as seen in Fig. 2 55 and which the flange should follow closely, will prevent a movement of the heel from side to side, because such is resisted by the plate fastened to the shank.

Secured at one end to the most prominently arched or curved portion of the plate is a leaf spring 10, which operates to uplift the shank of the shoe. It is preferred that the ends of the spring be secured to the plate by means of rivets 11 and that the spring be bowed in an upward direction so that its pressure will be fully applied to the shank of the shoe when the plate is fastened in its intended position. One end of the spring is slotted at 11, where it engages with the 65 next adjacent fastening rivet so that the spring will freely adapt itself to movements of the shank of the shoe. In this manner I correct that tendency of the foot to creep toward the forepart of the shoe. In other 70 words the foot is uniformly held in proper position above the shank at all times and the ligaments of the foot are therefore held against undue pressure through possible contact with the sides of the shoe at points 80 in advance of the arch. This further serves to prevent stagnation and materially corrects those inequalities in the shoe construction which commonly serve to create corns, bunions and undue pinching of the foot. 85

What is claimed is:—

The herein described arch support comprising a relatively rigid plate adapted to be secured to the under face of the shank of a shoe, and a cushioning device carried 90 by the plate and serving to establish pressure in an upward direction against the shank of the shoe to yieldingly advance the same against the arch of the foot.

In testimony whereof I affix my signature. 95

JAMES J. KEYS.
